UNITED STATES PATENT OFFICE

ANTHONY VANDERVELD, OF GRAND RAPIDS, MICHIGAN, ASSIGNOR TO GRAND RAPIDS STORE EQUIPMENT CORPORATION, OF GRAND RAPIDS, MICHIGAN, A CORPORATION OF MICHIGAN

COUNTER-PARTITION HOLDER

Application filed June 11, 1938. Serial No. 284,428.

This invention relates to a counter partition holder by means of which vertical partitions located above the top of a counter or table used in stores to carry and display articles of merchandise may be securely held in position, yet at the same time adjusted to different positions over the counter, in this manner altering the distances between adjacent partitions and thereby changing the sizes 10 of merchandise holding compartments defined by said partitions above the counter or table top.

The present invention is concerned with a simple and practical device of the character 15 noted which is easy to manufacture and install and which has novel means for permitting the adjustment stated and yet hold the partition holder with sufficient security against accidental movement when it has once 20 been adjusted to a desired position.

An understanding of the invention for the attainment of these ends may be had from the following description taken in connection with the accompanying drawing, in which—

25 Fig. 1 is a fragmentary perspective view, partly in section, illustrating the application of the partition holding device of my invention to the top of a counter or the like.

Fig. 2 is a fragmentary perspective view of 30 the lower end portion of the immediate partition holding member, with parts broken away and shown in section for better illustration of its construction.

Fig. 3 is a fragmentary vertical transverse 35 section through the counter top showing the immediate partition member in side elevation, and

Fig. 4 is a fragmentary sectional view similar to that shown in Fig. 2, showing the immediate partition member turned at right angles to the position it has in Fig. 3, which 40 position it takes in applying the member to or removing it from the channel guide in which it is mounted.

45 Like reference characters refer to like parts in the different figures of the drawing.

The invention is adapted to be applied to the top of a counter or table used in a store. 50 The top 1 shown in Fig. 1, usually of wood, at its opposed sides is equipped with vertical

border members 2 and its ends with similar vertical border members 3 which, extended above the top, define a large compartment over said top which may contain and hold articles of merchandise held by the counter or table for display and sale. It is desirable to divide the large compartment thus defined in smaller compartments, first, by using parallel vertical partitions extending across the table between border members at opposed edges 55 thereof. While the compartments thus made may later be sub-divided into still smaller compartments, the present invention is concerned with a means for adjustably holding the vertical partitions, usually of glass, securely yet adjustably above and across the table or counter top.

Near each side edge and preferably parallel to the edge of the top a groove is made in which a C-shaped channel of sheet metal is 60 located and secured. The channel has a horizontal lower web 4 and flanges 5 bent upwardly at each side edge for a short distance and then bent inwardly at right angles 65 toward each other, making the terminal flanges 6 which are separated by a longitudinal slot 7 extending the full length of the channel. The depth of the groove in the top 1 is such that the upper sides of the terminal flanges 6 are located flush with the upper side 70 of the top 1.

The immediate partition engaging and holding member is made of a length of flat metal formed into U-shape having a horizontal base 8 and two spaced apart upwardly 75 extending slightly converging fingers 9 which, at their extreme upper end portions, are bent outwardly from each other. Below the base 8 is a channel engaging member 10 of sheet metal which at its ends is formed with raised convex portions 11. A shouldered rivet or stud 12 is connected to the member 10 substantially midway between its ends extending upwardly therefrom and has a reduced portion passing through an opening 80 in the base 8 which is riveted over to make a countersunk head 13 lying flush with the upper side of the base 8 whereby the immediate partition engaging and holding member 85 is permanently connected to the channel 90 100

engaging member 10. The length of the rivet 12 is such that when the parts are connected, as described, the distance between the upper sides of the portions 11 and the under side of the base 8 is substantially that or 5 slightly less than the thickness of the terminal flanges 6 of the channel guide. The width of the member 10 is slightly less than the width of the slot 7 while its length is less 10 than the distance between the flanges 5 of the channel but greater than the width of said slot.

Any desired number of partition engaging and holding members may be applied to the 15 channel guide. The method of application, as shown in Fig. 4, is to place the member 10 over the slot lengthwise thereof whereby said member may be introduced into the channel guide and then turn the same 90° to the 20 position shown in Fig. 3. The raised portions 11 frictionally engage against the under sides of the terminal flanges 6 with the base 8 bearing closely against the upper sides thereof.

25 It is evident, accordingly, that the partition holding members consisting of the clip and member 10 connected thereto are frictionally held in any position on the channel guides to which they are adjusted, but that 30 the same can be moved lengthwise of the guides by the exertion of sufficient force to overcome the friction. The partitions 14 are of a length to extend the entire distance between the side border members 2 preferably, 35 so that the space above the top surrounded by the side and end border members is divided into a plurality of compartments of different widths which extend the full width of the top; and the widths of the compartments may be changed as desired by shifting 40 the partition holding members to different positions along the channel guides on which they are mounted.

The construction described is very practical and efficient for the purpose for which it 45 is designed, being simple to manufacture and durable in use. The invention is defined in the appended claims and is to be considered comprehensive of all forms of structure coming within their scope.

I claim:

50 1. The combination with a guide member comprising, an elongated channel, C-shaped in cross section, and having a longitudinal slot in a side thereof, of a U-shaped spring partition holding member located above and across said slot, and means connected to said partition holding member located within and across said slot and bearing against the inner 55 sides of said guide at opposite sides of said slot, said partition holding member bearing against the same parts of said guide at the outer sides thereof.

55 2. In a construction of the class described, 60 an elongated channel guide, a U-shaped

spring partition engaging and holding member, and means attached to said member received within and bearing frictionally against said channel whereby said member may be moved lengthwise of the channel and frictionally held in any position to which moved.

70 3. In a construction of the class described, an elongated channel guide, C-shaped in cross section, having a longitudinal slot in one side thereof, a member located within said channel having a width less than the width of said slot, and a length greater than the width thereof, a pin attached to said member at a point between its ends extending through said slot, and a U-shaped spring partition engaging and holding member connected with the outer end of said pin having a base longer than the width of said slot.

75 4. In a construction of the class described, an elongated channel guide, C-shaped in cross section, having a longitudinal slot in one side, a member located within the guide having a length greater than the width of said slot and a width less than the width thereof, said member at each end being formed with upwardly extending friction end portions, a pin attached to said member extending through the slot and a U-shaped spring partition engaging and holding member having a base longer than the width of said slot connected to the upper end of said pin, the distance between the under side of said base and the upper side of said friction end portions being such as to cause the under side of the base and said friction end portions to bear frictionally against opposite sides of the portions of the channel guides at each side of the slot therein.

80 In testimony whereof I affix my signature. 105
ANTHONY VANDERVELD.
